UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING AND ASSOCIATING MECHANISM.

1,318,043.

Specification of Letters Patent.

Patented Oct. 7, 1919.

Application filed January 31, 1918. Serial No. 214,758.

To all whom it may concern:

Be it known that I, HOWARD M. BARBER, a citizen of the United States, and resident of Stonington, in the county of New London 5 and State of Connecticut, have invented a new and useful Improvement in Sheet Collecting and Associating Mechanism, of which the following is a specification.

In sheet collecting and associating mechanism, it is very difficult to hold the sheets in 10 register on the collecting cylinder as the grippers open to collect the sheets and open to transfer the sheets. This is especially true where a number of sheets are to be collected and associated and transferred, and 15 where the sheets are heavy.

The object of my invention is to provide 20 novel means for insuring the proper holding of the sheets on the cylinder against slipping out of register while being collected, 25 associated and transferred, said means including a rotary carrier having end and side grippers which coöperate to collect a number of sheets fed from one source, such, for instance, as a source of main web sheet supply, and to combine therewith one or more extra sheets, such, for instance, as cover sheets fed from another source; the side grippers serving to hold the sheets which 30 are on the cylinder, in register, when the end grippers are opened to collect and to transfer the collected and associated sheets to a transfer cylinder, such, for instance, as a folding cylinder. The side grippers open 35 beyond the sides of the sheets as they pass the collection and transfer point so as not to interfere with the passage of the sheets.

A practical embodiment of my invention 40 is represented in the accompanying drawings, in which—

Figure 1 is a view in front elevation of so much of a sheet handling machine as includes my invention.

Fig. 2 is section taken in the plane of the 45 line II—II of Fig. 1,

Fig. 3 is a section taken in the plane of the line III—III of Fig. 1,

Fig. 4 is a section taken in the plane of the line IV—IV of Fig. 1, and

Fig. 5 is a detail section showing one of the side grippers and its operating cam.

One or more webs pass over the web feed

roll 1, and downwardly through the pair of coacting cutters 2, 3, and guides 4, 5, to the combined collecting and associating cylinder 55 6. The cylinder may have one or more sets of end grippers 7 and one or more corresponding sets of side grippers 8. In the present instance I have shown the cylinder 6 as having three sets of end grippers and 60 three sets of side grippers, the side grippers being located a considerable distance back of their end grippers so as to engage and grip the sheets at about midway their length. 65

The cylinder 9 is an extra sheet feeding cylinder arranged to feed one or more extra sheets to each of the collecting and associating surfaces of the cylinder 6. In the present instance, this cylinder 9 is arranged to 70 feed cover sheets to the cylinder 6 at the proper intervals, to be associated with the collected sheets thereon, as will hereinafter appear. The cylinder 9 is provided with a set of end grippers 10 arranged to take the 75 covers from a suitable feed table 11 and transfer them to the end grippers 7.

The cylinder 12 may be a folding cylinder and its set of end grippers 13 is arranged to take each group of collected and associated 80 main web and cover sheets from the end grippers 7, as well as the last sheets of the collection from the cutters 2, 3, at the proper times.

The grippers 10 are tumbler operated and 85 are closed to take the cover sheet from the table 11 every revolution of their cylinder 9, by the coaction of the tumbler cam 14 with the tumbler pin 15. The grippers 10 are opened to transfer their cover sheet to the 90 cylinder 6 every revolution of the cylinder 9, by the coaction of the tumbler cam 14 with the tumbler pin 16.

The grippers 13 of the folding cylinder 12 are operated every revolution of the cylinder 95 12 by the fixed cam 17 to engage and grip the collected and associated main web and cover sheets every one and one-third revolutions of the cylinder 6.

Each set of end grippers 7 on the cylinder 100 6 is opened by the engagement of the stationary cam 18 with the gripper stud or roller 19 at one end of the cylinder 6 every revolution of the cylinder to collect the

sheets cut from the main web or webs, and is opened every one and one-third revolutions of the cylinder 6, by the engagement of the two part movable cam 20, 21, with the gripper stud or roller 22 at the other end of the cylinder 6 to first transfer its collected and associated main web and cover sheets to the grippers 13 of the cylinder 12 and to then receive and grasp a cover sheet fed from the grippers 13 of the cover feeding cylinder 12. The part 20 of this two part cam is operated by a cam 23 carried by the folding cylinder 12 which engages a stud or roller 24 on the part 20; and the part 21 of the two part cam is operated by a cam 25 carried by the cover feeding cylinder 9 which engages a stud or roller 26 on the part 21. Springs 27, 28, serve to return the parts 20, 21, of the cam to their normal positions out of the path of the stud or roller 22 of the end grippers 7. The side grippers 8 of each set of the cylinder 6 are pivoted at the opposite ends of the cylinder on brackets 29, the gripping fingers of the grippers swinging through slots 30 in the cylinder into and out of their sheet engaging position. The grippers are held normally closed by springs 31 and are opened by the engagement of a stationary cam 32 with the gripper studs or rollers 33. The position and length of the cam are such that the side grippers are closed by their spring tension when the end grippers 7 are opened to receive the main web sheets, and also when they are opened to transfer the collected and associated main web and cover sheets to the folding cylinder 12, thus maintaining absolute control of the sheets which may be on the cylinder 6 and preventing them from slipping out of register. The cam 32 serves to swing the side gripper fingers out beyond the sides of the sheets as the side grippers pass the points where the main web sheets, and the cover sheets are taken as well as the point where the collected and associated main web and cover sheets are transferred to the folding cylinder.

From the above description, it will be seen that when a certain set of end grippers 7 on the cylinder 6 has been opened by the cam part 20 to transfer the collected and associated main web and cover sheets to the grippers 13 of the folding cylinder 12 (the last part of the main web sheet collection coming directly to the grippers 13 from the cutters 2, 3), the cam part 21 is caused to hold the end grippers open until they receive the cover sheet from the grippers 10 of the cylinder 9 when the end grippers are permitted to close on the cover sheet and carry it around into position to receive thereon the first part of the collection of main web sheets, the side grippers serving to close on the cover sheet as the end grippers open to collect.

It will also be seen that as the parts are shown, in the accompanying drawings, the cover sheet feeding cylinder and the folding cylinder each rotate once for every one and one-third rotation of the collecting and associating cylinder.

While I have disclosed my invention as applied to a three-way collecting cylinder arranged to collect four sheets or groups of sheets and associate a cover sheet therewith, it is obvious that I do not wish to limit myself to this particular arrangement.

What I claim is:—

1. Sheet collecting and associating mechanism including a combined collecting and associating cylinder having end and side grippers coöperating to collect a number of sheets and combine therewith one or more extra sheets. 80

2. Sheet collecting and associating mechanism including a combined collecting and associating cylinder having end and side grippers coöperating to collect a number of main web sheets and combine therewith a cover sheet. 85

3. Sheet collecting and associating mechanism including a combined collecting and associating cylinder having end and side grippers coöperating to collect a number of sheets, combine therewith one or more extra sheets and to transfer the so collected and associated sheets. 95

4. Sheet collecting and associating mechanism including a combined collecting and associating cylinder having end and side grippers coöperating to collect a number of main web sheets, combine therewith a cover sheet, and to transfer the so collected and associated sheets. 100

5. Sheet collecting and associating mechanism including a combined collecting and associating cylinder having end and side grippers coöperating to collect a number of sheets and combine therewith one or more extra sheets, the side grippers serving to close on and hold the sheets which are on the cylinder as the end grippers are opened to receive additional sheets. 105

6. Sheet collecting and associating mechanism including a combined collecting and associating cylinder having end and side grippers coöperating to collect a number of main web sheets and combine therewith a cover sheet, the side grippers serving to close on and hold the sheets which are on the cylinder as the end grippers are opened to receive additional sheets. 115

7. Sheet collecting and associating mechanism including a combined collecting and associating cylinder having end and side grippers coöperating to collect a number of sheets and combine therewith one or more extra sheets, the side grippers serving to close on and hold the sheets which are on the cylinder as the end grippers are opened to 120

130

receive additional sheets and also as the end grippers are opened to transfer the so collected and associated sheets.

8. Sheet collecting and associating mech-

anism including a combined collecting and associating cylinder having end and side grippers coöperating to collect a number of main web sheets and combine therewith a cover sheet, the side grippers serving to close on and hold the sheets which are on the cylinder as the end grippers are opened to receive additional sheets and also as the end grippers are opened to transfer the so collected and associated sheets.

15 9. Sheet collecting and associating mechanism including web sheet cutters and a combined collecting and associating cylinder having end grippers arranged to take one or more extra sheets and to collect sheets fed from the cutters and side grippers arranged to hold the sheets which are on the cylinder as the end grippers are opened to collect.

10. Sheet collecting and associating mechanism including web sheet cutters and a combined collecting and associating cylinder having end grippers arranged to take a cover sheet and to collect thereon sheets fed from the cutters and side grippers arranged to hold the sheets which are on the cylinder as the end grippers are opened to collect.

11. Sheet collecting and associating mechanism including web sheet cutters, a transfer cylinder and a combined collecting and associating cylinder having end grippers arranged to take one or more extra sheets and to collect the sheets fed from the cutters and to transfer the so collected and associated sheets to the transfer cylinder, and side grippers arranged to hold the sheets which are on the collecting and associating cylinder as the end grippers are opened to collect.

12. Sheet collecting and associating mechanism including web sheet cutters, a transfer cylinder and a combined collecting and associating cylinder having end grippers arranged to take a cover sheet and to collect thereon sheets fed from the cutters and to transfer the so collected and associated sheets to the transfer cylinder, and side grippers arranged to hold the sheets which are on the collecting and associating cylinder as the end grippers are opened to collect.

13. Sheet collecting and associating mechanism including a combined collecting and associating cylinder having coöperating end and side grippers arranged to alternately engage and hold successive sheets of a collection on the cylinder and to engage and hold one or more extra sheets to be combined with said collection.

14. Sheet collecting and associating mechanism including a combined collecting and associating cylinder having coöperating end and side grippers arranged to alternately

engage and hold successive sheets of a collection on the cylinder and to engage and hold a cover sheet to be combined with the said collection.

15. Sheet collecting and associating mech- 70 anism including web sheet cutters and a combined collecting and associating cylinder having coöperating end and side grippers arranged to alternately engage and hold successive web sheets of a collection on the 75 cylinder, and to engage and hold one or more extra sheets to be combined with the said collection.

16. Sheet collecting and associating mech- 80 anism including web sheet cutters and a combined collecting and associating cylinder having coöperating end and side grippers arranged to alternately engage and hold successive web sheets of a collection on the cyl- 85 inder and to engage and hold a cover sheet to be combined with the said collection.

17. Sheet collecting and associating mech- 90 anism including web sheet cutters, a transfer cylinder, and a combined collecting and associating cylinder having coöperating end and side grippers arranged to alternately engage and hold successive web sheets of a collection on the cylinder and to engage and hold one or more extra sheets to be combined with said collection, the side grippers serv- 95 ing to hold the so collected and associated sheets as the end grippers are opened to transfer the same to the transfer cylinder.

18. Sheet collecting and associating mech- 100 anism including web sheet cutters, a folding cylinder and a combined collecting and associating cylinder having coöperating end and side grippers arranged to alternately engage and hold successive web sheets of a collection on the cylinder and to engage and 105 hold a cover sheet to be combined with said collection, the side grippers serving to hold the so collected and associated sheets as the end grippers are opened to transfer the same to the folding cylinder.

19. Sheet collecting and associating mech- 110 anism including a combined collecting and associating cylinder having an extra sheet taking point and a main web sheet collect- 115 ing point, means for feeding the sheets to said points, and end and side grippers on the cylinder coöperating to take one or more extra sheets and to collect the main web sheets, the side grippers being arranged to hold the sheets which are on the cylinder as the end grippers are opened at the sheet collecting point.

20. Sheet collecting and associating mech- 120 anism including a combined collecting and associating cylinder having a cover sheet taking point and a main web sheet collect- 125 ing point, means for feeding the sheets to said points, and end and side grippers on the cylinder coöperating to take a cover sheet and to collect the main web sheets 130.

- thereon, the side grippers being arranged to hold the sheets which are on the collecting and associating cylinder as the end grippers are opened at the sheet collecting point.
5. 21. Sheet collecting and associating mechanism including a combined sheet collecting and associating cylinder, an extra sheet taking point and a main web sheet collecting and transfer point, means for feeding sheets to said points, and end and side grippers on the cylinder co-operating to take one or more extra sheets and to collect the main web sheets and to transfer the so collected and associated sheets, the side grippers being arranged to hold the sheets which are on the collecting cylinder as the end grippers are opened at the sheet collecting and transfer point.
10. 22. Sheet collecting and associating mechanism including a combined sheet collecting and associating cylinder having a cover sheet taking point and a main web sheet collecting and transfer point, means for feeding the sheets to said points, and end and side grippers on the cylinder co-operating to take a cover sheet and to collect the main web sheets thereon and to transfer the so collected and associated sheets, the side grippers being arranged to hold the sheets which are on the collecting cylinder as the end grippers are opened at the sheet collecting and transfer points.
15. 23. Sheet collecting and associating mechanism including a combined sheet collecting and associating cylinder having an extra sheet taking point, means for feeding extra sheets to said point, a main web sheet collecting point, means for cutting sheets from the web or webs and feeding them to said collecting point, and end and side grippers on the cylinder co-operating to take one or more extra sheets and to collect the main web sheets, the side grippers being arranged to hold the sheets which are on the collecting and associating cylinder as the end grippers are opened at the sheet collecting point.
20. 24. Sheet collecting and associating mechanism including a combined sheet collecting and associating cylinder having a cover sheet taking point, means for feeding cover sheets to said point, a main web sheet collecting point, means for cutting sheets from a web or webs and feeding them to said collecting point, and end and side grippers on the cylinder co-operating to take a cover sheet and to collect the main web sheets thereon, the side grippers being arranged to hold the sheets which are on the collecting and associating cylinder as the end grippers are opened at the sheet collecting point.
25. 25. Sheet collecting and associating mechanism including a combined sheet collecting and associating cylinder having an extra sheet taking point, means for feeding extra sheets to said point, a main web sheet collecting and transfer point, means for cutting sheets from the web or webs and feeding them to said collecting point, and end and side grippers on the cylinder co-operating to take one or more extra sheets and to collect the main web sheets and to transfer the so collected and associated sheets, the side grippers being arranged to hold the sheets which are on the collecting cylinder as the end grippers are opened at the sheet collecting and transfer point.
30. 26. Sheet collecting and associating mechanism including a combined sheet collecting and associating cylinder having a cover sheet taking point, means for feeding cover sheets to said point, a main web sheet collecting and transfer point, means for cutting sheets from the web or webs and feeding them to said collecting point, and end and side grippers on the cylinder co-operating to take a cover sheet and to collect the main web sheet thereon and to transfer the so collected and associated sheets, the said grippers being arranged to hold the sheets which are on the collecting and associating cylinder as the end grippers are opened at the sheet collecting and transfer point.
35. 27. Sheet collecting and associating mechanism including a combined collecting and associating cylinder having end and side grippers co-operating to collect thereon sheets fed from one source and to combine therewith one or more sheets fed from another source.
40. 28. Sheet collecting and associating mechanism including a combined collecting and associating cylinder having end and side grippers co-acting to collect thereon main web sheets fed from one source and to combine therewith a cover sheet fed from another source.
45. 29. Sheet collecting and associating mechanism including a combined collecting and associating cylinder having co-operating end and side grippers, the end grippers operating to take an extra sheet and to collect successive main web sheets, the side grippers operating to hold the sheets which are on the cylinder as the end grippers are opened to collect the main web sheets.
50. 30. Sheet collecting and associating mechanism including a combined collecting and associating cylinder having co-operating end and side grippers, the end grippers operating to take a cover sheet and to collect successive main web sheets, the side grippers operating to hold the sheets which are on the cylinder as the end grippers are opened to collect the web sheets.
55. 31. Sheet collecting and associating mechanism including a combined collecting and associating cylinder having co-operating end and side grippers, the end grippers operating to take one or more extra sheets at one point and to collect main web sheets at another point, the side grippers operating to

hold the sheets which are on the cylinder as the end grippers are opened at the collection point.

32. Sheet collecting and associating mechanism including a combined collecting and associating cylinder having coöperating end and side grippers, the end grippers operating to take a cover sheet at one point and

to collect main web sheets at another point, the side grippers operating to hold the sheets which are on the cylinder as the end grippers are opened at the collection point. 10

In testimony, that I claim the foregoing as my invention, I have signed my name this thirtieth day of January, 1918.

HOWARD M. BARBER.
